PUMPING JACK

Fred H. Rued, Lafayette, Calif., assignor to The
Pelton Water Wheel Company, San Francisco,
Calif., a corporation of California

Application May 6, 1946, Serial No. 667,717

7 Claims. (Cl. 60—52)

1

My invention relates to means for pumping oil or other liquids from deep wells and has to do with a pumping jack for this purpose employing a balancing tank containing oil for operating the jack and also containing a supply of air. More especially the invention has to do with means for maintaining the balancing tank air supply.

In the operation of a pumping jack the necessary supply of air becomes dissipated and it becomes desirable to furnish some means which is automatic in nature for replenishing the air supply and for maintaining a set or established air pressure within the balancing tank.

Although there are various ways of arranging for such a make-up air supply the schemes heretofore proposed are not entirely satisfactory in practice partly because of the relatively minor quantities involved and partly because of the necessity for regulating the pressure at substantially a set value or to vary only within approximately a fixed range.

It is therefore an object of my invention to provide in a pumping jack an air supply for the balancing tank which is in general an improvement over those heretofore known.

Another object of the invention is to provide an air pump which is capable of supplying the relatively small quantities of air required from time to time without employing a good deal of complicated mechanism.

Another object of the invention is to provide in a pumping jack a means to maintain the air in the balancing tank substantially at the desired pressure.

It is a further object of the invention in general to improve pumping jacks.

Other objects together with the foregoing are attained in the embodiment of the invention disclosed in accompanying drawings, in which

Figure 1 is a diagrammatic showing of a pumping jack system incorporating the air pumping mechanism of the present invention.

Figure 2 is a side elevation of the main pump and valve arrangement of the pumping jack, certain portions being broken away to disclose the interior construction in cross section on substantially a vertical diametral plane and other portions being omitted to reduce the size of the figure.

Figure 3 is a perspective showing in cross section the air pump regulating valve employed in connection with my invention.

Figure 4 is a cross section, the plane of which is indicated by the line 4—4 of Figure 3.

Figure 5 is an isometric perspective showing in cross section the pilot valve utilized in connection with my invention.

Figure 6 is a cross section, the plane of which is indicated by the line 6—6 of Figure 5.

2

In the particular form of pumping jack shown diagrammatically there is provided a balancing tank 6, containing hydraulic fluid such as oil 7, that is permitted to egress from the tank through an opening 8, into a valve body 9 and from there into a conduit 11 leading to the inlet 12 of a main valve body 13. A valve bobbin 14 is translatable or reciprocable within the valve body and in the extreme position shown in Figure 1 permits the passage of the oil from the inlet 12 through the interior of the main valve body to an outlet 16 therefrom. A conduit 17 extends from the outlet to an inlet 18 of a main circulating pump 19 driven by any suitable sort of prime mover. Oil which has entered the pump 19 is discharged therefrom at an increased pressure through an outlet opening 21, connected by a duct 22 to the main valve body 13. The pumped oil enters the valve body through an opening 23 and in the position of the valve bobbin 14 shown in Figure 1 traverses the interior of the valve body and emerges therefrom through an outlet 24. A hydraulic conductor 26 leads from the outlet 24 to a line 27 connected to an aperture 28 in an appropriate lower part of a hydraulic jack cylinder 29. Adapted to reciprocate within the cylinder 29 is a hydraulic jack piston 31 carrying a piston rod or polish rod 32 emerging from the lower end of the cylinder 29 and appropriately connected to a deep well pump (not shown).

The piston 31 is designed to reciprocate within the cylinder 29 and under the conditions just described is urged upwardly in the cylinder by the pressure of the oil flowing into the entrance aperture 28. This condition of operation continues until such time as the piston 31 overrides one of a series of upper stroke limit apertures 33. These are connected by a series of ducts 34 to a selector valve 36 in which one of the ducts is connected by a passage 37 to a control pipe line 38. In this line there is disposed a check valve 41, permitting flow therethrough in the direction of the indicated arrow and blocking flow in the reverse direction. Flow through the check valve might be expected to continue through a line 42 containing a similar check valve 43 to any one of series of lower stroke limit apertures 44, all of which are provided with valves 46 capable of serving either as check valves permitting flow in the direction of the indicated arrow or of being manually closed to block flow altogether. One of the valves 46, however, normally is left open to serve as a lower stroke limit check. But since the pressure below the piston 31 is substantially uniform throughout all of the piping system connected to the cylinder, flow does not take place through the pipe line 42 but rather does occur in a pipeline 47 interposed between the checks 41 and 43, and extending through a manually con-

trolled valve 48 to one end of a pilot valve housing 49. The pilot valve is preferably, as shown in Figure 2, mounted on the top of the casing 13 of the main valve, which in turn is mounted on top of the pump 19. The valve casing 49 is a body having an interior cavity divided into various portions. Within the body there is provided a chamber 51 with which the pipe 47 communicates, and within which a piston 52 of substantial cross-sectional area is reciprocable.

Joined to the piston 52 by a reduced stem 53 is a valve head 54 of an appropriate smaller diameter to be reciprocable within a sleeve 56, located within the casing 49. A stem 57 connects the head 54 with a similar head 58, while an end stem 59 serves as a stop. The diameter or area of the heads 54 and 58 is substantially less than that of the piston 52 so that when pressure exists on the end of the piston 52 the tendency is for the piston and the heads 57 and 58 as well as the intermediate stems, all together constituting a valve bobbin, to be translated to the left hand extreme position from that shown in Figure 1. Any leakage past the piston 52 flows into a pipe line 61 joined to an outlet 62 in the pilot valve body 49 and also continuing to a scavenger pump 63 driven by any suitable source of power and discharging into a pipe line 64, containing a check valve 66, and joined to the balancing tank 6 at an inlet 67.

Furthermore, in the position of the pilot valve shown in Figure 1, the heads 54 and 58 are so located with respect to ports 68 and 69 in the sleeve 56 that the interior of the sleeve is in communication with the scavenger pipe 61 so that the pressure from the line 47 upon the piston 52 is effective to translate the pilot valve bobbin. When this occurs, fluid from the central chamber 71 of the main valve passes through a pipe 72 into a pressure chamber 73 within the pilot valve housing and flows through ports 74 in the sleeve to the space between the heads 54 and 58 and continues then to flow through a sleeve port 69 into a duct 76. This extends to a pipe 77 leading to a chamber 78 at one end of the main valve housing 13, and containing a piston 79. The other end of the pipe 77 connects through an aperture 81 with the chamber 51 containing the piston 52 always in a position to block any pressure flow into such chamber.

However the pressure against one side of the piston 79 forces a translation of the main valve 14 in accordance with the immediately preceding translation of the pilot valve which in turn moves in response to the operation of the jack piston 31. When the bobbin of the main valve translates to the left from the position shown in Figure 1, a head 82 on the valve bobbin cuts off flow from the central chamber 71 through the outlet 24 while a head 85 shifts so that the flow from the central chamber proceeds through the outlet 12. In addition, the head 82 shifting to the left establishes free communication between the port 24, connected by the pipeline 26 and the pipeline 27 to the interior of the cylinder 29, and a port 83 connected by a pipe 84 to an inlet 86 to the pump 19. The pipe 84 is also joined by a shunt pipe 87 to the inlet pipe 17.

Under these circumstances the operation of the pump 19 is effective to withdraw oil from below the jack piston 31 through the aperture 28, the pipe 27 and the pipe 26 and through the main valve body into the port 83 and through the pipes 87 and 84 into the inlets 18 and 86 of the pump. In this position of the main valve, discharge 75

from the pump 19 proceeds through the central pump chamber 71 into and through the port 12 and through the connecting pipe 11 back through the valve body 9 and the port 8 to the balancing tank 6. Oil being transferred from beneath the jack piston to the balancing tank, the piston lowers and continues such action until it overrides the particular one of the lower stroke limit valves 46 which happens to be selected as open. 10 When such port is overridden the pressure previously existing therein is relieved inasmuch as the pressure above the piston is atmospheric or substantially so, and this release in the pressure permits flow through the pipe 42 and past the check 43, as well as through the pipe 41 and the hand valve 48, to the chamber 51 within which the piston 52 is situated.

Since the pressure acting upon the end of such piston 52 is then substantially atmospheric, whereas the pressure operating on the head 58 at the other end of the valve bobbin is that of the pump central chamber 71 or substantially so, the pilot valve bobbin is restored by reciprocation from its left hand position back into its right hand position as seen in Figure 1. When such motion of the pilot shuttle occurs the pressure fluid from the pump chamber 71 is blocked from flowing out of the chamber 73 through the port 74 inasmuch as the head 58 prevents such flow. At 20 the same time the head 54 has shifted so that appropriate flow occurs from the chamber 78 through the line 77 and the pipe 76 through the port 69 and thence through the port 68 into the pilot valve chamber, and from thence 25 through the outlet 62 through the line 61 back to the scavenging pump 63 and to the balancing tank 6.

There is provided a means for shutting down the entire system in the event of breakage of the piston rod 32 or any connected appurtenances 10 which reduce the pressure beneath the piston 31. For that reason the line 27, which is in communication with the cylinder 29 below the piston 31, is connected through a hand valve 91 to a cylinder 92, by means of a pipe 93. In the cylinder 92 a piston 94 is reciprocable and the piston itself is connected by a stem 96 to a poppet valve 97 normally held open by the pressure exerted through the lines 27 and 93 on the piston 94, and therefore permitting flow from the balancing tank 45 through the valve body 9 to the pump 19. However, when the pressure in the line 93 fails, due to failure of the pressure within the cylinder 29, it is no longer effective upon the piston 94 and the superior pressure upon such piston and upon the 50 valve 97 from the interior of the tank 6 is effective immediately to shut the valve 97 and to block flow through the body 9 and pipe 11 thus depriving the system of its operating fluid and causing it to shut down. To make sure that the piston 94 is 55 readily operable any leakage thereby is drained off through a port 98 into a line 99 connected by a pipe 101 to the scavenging line 61 and such leakage is therefore returned to the tank 6.

Sometimes it is difficult to re-establish flow past 60 the valve 97, that is to re-open the valve in re-starting the mechanism after repairing any difficulty which may have caused it automatically to shut down, and for that reason I provide a shunt line 102 around the valve 97 and in the shunt line 65 interpose a manually controlled valve 103 normally shut but readily operable when needed.

Furthermore there is provided a structure for effectuating a slowing down or retardation of the system in the event under some unusual circumstances the scavenging line 61 or its connecting

lines should become clogged or overloaded to the point that the scavenge pump 63 could not handle the volume. Under those circumstances the pressure within the scavenge line 61, for example, increases and is transmitted through the pipe 101 and through a hand valve 104 into a line 106, which has communication through a port 107 with one side of a piston 108 operating in a relief valve chamber 109. The other side of the piston 108 is in communication through a port 111 with a line 112 leading to a spring pressed relief valve 113 opening through a port 114 to the atmosphere.

Within the relief valve chamber 109 is a spring 116 provided with an adjusting stem 117 to regulate its pressure upon the piston 108 and likewise there is provided a poppet valve 118 effective to control flow through the valve chamber 109 past a seat 119. Communicating with the valve chamber on one side of the seat 119 is a pipe 121 leading to the pump outlet or high pressure side 21, while communicating with the other side of the seat 119 through a pipe 122 is the pressure on the intake or low pressure side of the pump. Under these circumstances whenever pressure in the scavenge line exceeds a predetermined value, the resulting flow through the port 107 displaces the piston 108 toward the right in Figure 1, discharging any otherwise trapped fluid from the chamber 109 through the duct 111 and pipe 112 to the atmosphere through the relief valve 113. Simultaneously the spring 116 is compressed from its adjusted value and oil is permitted to flow from the outlet side of the pump through the pipe 121 and past the valve seat 119, then through the pipe 122 to the pump inlet. Since this is a short circuit or shunt flow the major output of the pump is diverted locally and the remainder only is utilized in actuating the pumping jack system. Thus the system is operated at a reduced rate until such time as the scavenge pump 63 is effective to remove the excess oil from the scavenge system and to reduce the pressure existing therein. Upon the occurrence of that event the pressure acting on the piston 108 through the port 107 is reduced, the spring 116 is again effective to seat the valve 119, thus blocking the short circuit or shunt flow through the main pump and restoring the parts to the position shown in Figure 1.

Under these conditions, the relief valve 113 closes under the influence of its spring and any leakage past the piston 108 drains through the line 107 and through the pipe 111 past a check valve 123 into the line 106 and into the scavenge line 61. The valve 104 is for manual operation in the event it is ever desired to impose the pressure existing within the balancing tank 6 upon the piston 108 for trial operation of the overload system. Comparably, the valve 91 is for manual operation in the event it is desired to connect the emergency shut down valve 97 with the scavenge system in order to shut off the operation of the pumping jack. Similarly, the valve 48 permits manual operation of the pilot valve.

As so far described the pumping jack is primarily a hydraulic implement operated by a fluid such as oil. In addition, however, the balancing tank 6 contains a volume 126 of atmospheric air at an elevated pressure, in fact at the same pressure as the oil body 7, to serve as a cushion for the varying oil volume in the balancing chamber. The air body 126 is subject not only to expansion and contraction but is also subject to depletion due to leakage and other causes, and for that reason there is provided a means for affording make-up

or additional air to the volume 126 so as to maintain an air supply at a predetermined pressure.

In accordance with my invention there is provided an air pump generally designated 127, incorporated with the main valve. The air pump (Figure 2) comprises a head 128 removably secured to one end of the main valve body 13 and defining an air compressor cylinder 129. Designed to operate in such cylinder is an air compressor piston 131 provided with suitable sealing rings 132 thereon and connected by a suitable junction 133 to the reciprocating bobbin 14 of the main valve. Thus as the main valve bobbin reciprocates the air compressor piston 131 is concurrently reciprocated to vary the volume of the chamber 129. Air which is inspirated during the instroke of the piston 131 is compressed during an outstroke and is discharged from the chamber 129 through an outlet check valve 134 normally urged closed by an outlet spring 136. The compressed air flows through a pipe 137 to a secondary check valve 138 and through a port 139 into the balancing tank 6.

Air for supplying the air compressor is inducted from the atmosphere through a filter if desired (not shown) and through a line 141 leading into a control valve body 142. The air enters a chamber 143 within the body 142 and passes through an annular barrier 144 to an outlet duct 146 connected by a conduit 147 to an inlet check valve chamber 148. Within such chamber is a thimble 149, affording communication with the duct 147 and with a port 151 merging with the chamber 129 and carrying a gravitationally closed check valve 152. A groove on the side of the thimble affords free access of air from one side thereof to the other. During an intake stroke of the piston 131, air is drawn through the duct 141 to the chamber 143 through the barrier 144 and through the duct 146 past the thereupon opened check valve 152 into the compressor cylinder. As soon, however, as the compressor piston 131 traverses the duct 151 the duct is blocked and the trapped air within the chamber is compressed and expelled. During the outward or discharge stroke of the piston 131 the check valve 152 seats on the thimble and prevents retrogressive air flow.

In accordance with the invention, means are provided for regulating the operation of the air compressor so that the air contained within the tank 6 is maintained at substantially the desired pressure at all times. For this reason within the body 142 there is provided a piston 156 which is reciprocable within a cylinder 157 formed in the body. The piston motion is under the influence of 50 and is in response to the pressure of oil derived from the tank 6 and communicated through the line 11 and through a branch conduit 158 joined to the inlet 12 of the main valve body 13. The tendency of the oil is to communicate the tank 55 pressure to the piston to translate the piston 156 to the left. Movement of the piston to the left is resisted by a coil spring 159 contained in an extension 161 of the body 142 and bearing at one end upon a thimble 162. A needle 163 spans the 60 space between the thimble and a depression 164 in the piston 156 to take care of any minor misalignment between the thimble and the piston. The other end of the spring 159 bears against a cap 166 adjusted in position by a screw 167 in the 65 threaded end 168 of the body 161 and held in adjusted relationship by a lock nut 169 and a cap nut 171.

By appropriately adjusting the screw 167 and holding the adjustment by means of the nuts 169 70 and 171, a predetermined spring pressure is

transmitted to the piston 156. The spring 159 normally holds the piston against an end plug 172 in the body 142 while the pressure on the piston transmitted through the conduit 158 is under a predetermined value. During such time the parts are substantially as shown in Figure 3 so that air flows freely from the atmosphere through the regulating body 142 to the air compressor and is pumped from there to the tank 6. Thus all the time that the main valve reciprocates under the influence of the pilot valve, in turn responsive to the reciprocation of the pumping jack, air is compressed into the tank 6. Continuance of such operation increases the pressure within the tank until such time as it is sufficient, being transmitted through the conduit 158, to force the piston 156 toward the left in Figure 3. The spring 159 is compressed until such time as the piston 156 rides to the left sufficiently to occupy all of the space within the annulus 144 and to block flow from the inlet 141 through the body 142 to the pump. This starves the air pump of air. Under these circumstances a movement of the air compressor piston 131 toward the right in Figure 2 is ineffective to lift the check valve 152 from its seat because of the absence of air flow to the check valve. Air flow to the air compressor is entirely interrupted and although it reciprocates, the compressor does so idly without displacing any air through the duct 137 into the tank 6.

The air compressor is not effective to charge any additional air into the tank 6 until such time as leakage or other causes reduce the pressure in the air volume 126. When that occurs then the pressure transmitted from the tank by the oil body is then effective through the pipe 11 and the conduit 158 to relax the pressure slightly upon the piston 156. The spring 159 becomes again effective due to its then superior urgency to translate the piston 156 from its position blocking the annulus 144 back into the position shown in Figure 3, wherein the annulus 144 is again entirely free and air can flow from the inlet 141 through the controller valve body 142 and through the duct 147 past the check valve 152 into the air compressor. As the compressor continually reciprocates under the influence of the bobbin 14 of the main valve, it is again made effective to supply air to the tank 6, thus completing a make-up cycle.

This operation repeats itself from time to time under fluctuations in pressure within the tank 6 and the net result is to keep the tank charged with air at an appropriate pressure. The pressure is determined hydraulically by the fluid being pumped by the main pump in response to reciprocatory movement of the main valve, which in turn corresponds not only to reciprocation of the pilot or shuttle valve but likewise corresponds to operation of the jack piston 31. In accordance with my invention, therefore, I provide a pumping jack in which the supply of air or the body of air effective in the balancing tank is made up from time to time as indicated by the pressure requirements.

I claim:

1. In a pumping jack having a balancing tank, a pump drawing from said balancing tank, and a reciprocating main valve controlling flow from said pump, the combination of a reciprocating air

pump, means for conducting air from said air pump to said tank, and means for reciprocating said air pump by the reciprocation of said main valve.

5 2. In a pumping jack having a balancing tank for air and oil, an oil pump drawing oil from said balancing tank, and a reciprocating main valve controlling oil flow from said pump, the combination of a reciprocating air pump, means for conducting air from said pump to said tank, and means for mechanically connecting said air pump and said valve for conjoint reciprocation.

15 3. In a pumping jack having a balancing tank for air and oil, an oil pump drawing oil from said balancing tank, and a main valve having a reciprocating bobbin controlling oil flow from said pump, the combination of an air pump having a piston, means for conducting air from said air pump to said tank, and means for connecting said bobbin and said piston.

20 4. In a pumping jack having a balancing tank for air and oil, an oil pump drawing oil from said balancing tank, and a main valve having a reciprocating bobbin controlling oil flow from said pump, the combination of an air pump having a piston, means for conducting air from said air pump to said tank, means joining said piston and said bobbin, and means responsive to oil pressure for disabling said air pump.

25 5. In a pumping jack having a jack cylinder, a jack piston, a balancing tank for air and oil, an oil pump drawing oil from said balancing tank, and a main valve having a bobbin controlling oil flow from said pump to said cylinder, the combination of means for reciprocating said bobbin in accordance with the position of said jack piston, an air pump having a piston, means for connecting said air pump piston and said bobbin, and means for supplying air from said air pump to said tank.

30 6. In a pumping jack having a jack cylinder, a jack piston, a balancing tank for air and oil, an oil pump drawing oil from said balancing tank, a main valve having a reciprocating bobbin for controlling oil flow from said pump to said jack cylinder, and a pilot valve responsive to motion of said jack piston for controlling the operation of said main valve, the combination of an air pump for supplying air to said tank, and means on said bobbin for driving said air pump.

35 7. In a pumping jack having a jack cylinder, a jack piston, a balancing tank for air and oil, an oil pump drawing oil from said balancing tank, a valve having a reciprocating bobbin responsive to the position of said piston for controlling oil flow from said pump to said cylinder, the combination of means driven by said bobbin for supplying air to said tank.
